DESIGN FOR A REGISTER

William C. De Roo and Alfred E. Kietzmann,
Holland, Mich., assignors to Hart & Cooley
Manufacturing Company, Holland, Mich., a corporation of Delaware

Application August 22, 1940, Serial No. 94,571

Term of patent 14 years

To all whom it may concern:

Be it known that we, William C. De Roo and Alfred E. Kietzmann, citizens of the United States, residing at Holland, in the county of Ottawa and State of Michigan, have invented a new, original, and ornamental Design for Registers, of which the following is a specification, reference being had to the accompanying drawing, forming part thereof.

Fig. 1 is a front elevational view of a register showing our new design.

Fig. 2 is a top plan view of the same, and
Fig. 3 is an end elevational view of the same.
We claim:
The ornamental design for a register, as shown.

WILLIAM C. DE ROO.
ALFRED E. KIETZMANN.
